UNITED STATES PATENT OFFICE.

HENRY FAWCETT, OF KIDDERMINSTER, ENGLAND, ASSIGNOR TO
J. & J. DOBSON, OF PHILADELPHIA, PENNSYLVANIA.

DESIGN FOR A CARPET.

SPECIFICATION forming part of Design No. 17,997, dated January 3, 1889.

Application filed September 28, 1887. Serial No. 250,978. Term of patent 7 years.

To all whom it may concern:

Be it known that I, HENRY FAWCETT, a subject of the Queen of Great Britain, residing at Kidderminster, England, have invented and produced a certain new and original Design for Carpets, of which the following is a full, clear, and exact description, reference being had to the accompanying drawing, forming a part of this specification.

10 My design is applicable more particularly to loop and cut pile carpets and to those woven with a border. As illustrated in the drawing, it consists of a center or body proper, composed of squares of irregular figures appropriately grouped, and a double border, the inner consisting of three parallel rows of figures, the central one of much greater width than the other two and contrasting with them, the

outer border being composed of an inner row of figures and an outer dark ground with angular figures thereon. 20

I claim—

1. The design for the center or body of the carpet, substantially as shown and described.
2. The design for the border of the carpet, 25 substantially as shown and described.
3. The design for a bordered carpet, consisting of the center and border, substantially as shown and described.

In testimony whereof I have hereunto affixed my signature this 24th day of May, A. D. 1887.

HENRY FAWCETT.
